UNITED STATES PATENT OFFICE.

ADELINE E. MALONE, OF SAN FRANCISCO, CALIFORNIA.

DESIGN FOR A DOLL.

55,428.

Specification for Design.

Patented June 8, 1920.

Application filed February 6, 1920. Serial No. 358,142. Term of patent 14 years.

To all whom it may concern:

Be it known that I, ADELINE E. MALONE, a citizen of the United States, residing in the city and county of San Francisco and State of California, have invented a new, original, and ornamental Design for a Doll, of which the following is a specification, reference being had to the accompanying drawing, forming part thereof,

Figure 1 is a front elevation of a doll, and Fig. 2 is a side elevation of a doll, showing my new design.

I claim:

The ornamental design for a doll, as shown.

ADELINE E. MALONE.
